(57) **CLAIM**

The ornamental design for a clip, as shown and described.

DESCRIPTION

FIG. 1 is a first perspective view showing a right side of a clip.

FIG. 2 is a second perspective view showing a left side of the clip of FIG. 1.

FIG. 3 is a front view of the clip of FIG. 1.

FIG. 4 is a rear view of the clip of FIG. 1.

FIG. 5 is a left side view of the clip of FIG. 1.

FIG. 6 is a right side view of the clip of FIG. 1.

FIG. 7 is a top view of the clip of FIG. 1; and,

FIG. 8 is a bottom view of the clip of FIG. 1.

Where utilized, the broken lines show portions of the clip that form no part of the claimed design.
